Inventor:-

Arthur Frederick Richmond Cotton,

By:-

Fowler & Smith,

Atty.

UNITED STATES PATENT OFFICE.

ARTHUR FREDERICK RICHMOND COTTON, OF LONDON, ENGLAND.

SOUND BOX.

Application filed July 16, 1923. Serial No. 651,807.

To all whom it may concern:

Be it known that I, ARTHUR FREDERICK RICHMOND COTTON, a subject of the King of England, and residing at 9 Wetherby 5 Gardens, London, S. W. 5, England, have invented certain new and useful Improvements in Sound Boxes, of which the following is a specification.

This invention relates to gramophones 10 and the like, and consists of an improved construction of sound-box for such instruments.

The invention has for object to provide a simple and secure pivotal mounting 15 of the stylus lever, with a minimum of metallic connection between the latter and the body of the sound-box, the lever being held in place by means of the control springs.

According to this invention, the stylus 20 lever is provided with an apertured base or plate, which rocks together with the stylus lever upon knife-edges or points mounted upon the rim of the sound-box, the plate being held in contact with said knife-edges or points by means of leaf-springs, 25 preferably laminated and constructed of whalebone, which are fitted in the apertures in the plate and secured at their centres against the rim of the sound-box, the springs 30 bearing upon the sides of the plate at the opposite ends of the apertures so as to control the rocking motion of the plate and stylus lever.

The invention has also for object to provide the sound-box with a resonating chamber, which absorbs any harsh notes set up in worn records and also gives increased detail in orchestral music.

The accompanying drawings illustrate the 40 preferred construction of the sound-box:—

Figure 1 is a front elevation.

Figure 2 is a side view in section on the line 2—2 of Figure 1.

Figures 3 and 4 represent in section and 45 plan respectively the stylus lever and its apertured base plate.

The sound-box is shown comprising a body formed by the assembly of a number of coaxial plates or sections; of these, the 50 aluminum plate 10 having a boss 11, lined with a rubber ring 12 is adapted to slide upon the swan-neck or equivalent extremity of the tone-arm, shown in dotted lines in Figure 2. The plate 10 is attached by screws 13 to a recessed brass plate 14, a disc 15 of black vulcanized fibre being inter-

posed to prevent metallic resonance. The front or end plate 16 attached by screws 17 to the opposite side of the plate 14 carries the mica or other diaphragm 18 held at its periphery between solid rubber rings 19, 20 of rectangular section.

The plate 14 has an annular recess 21 upon its forward face, this recess being covered by a second diaphragm 22 of annular shape, held at its outer periphery by the pressure of the rubber ring 20 against the plate 14, and gripped around its inner periphery by the flange 23 of a hollow bush 24 screwing into the centre of the plate 14. The recess 21 is filled with petroleum jelly, causing it to act as a resonating chamber, which absorbs any harsh notes or scratching of the record, and gives increased detail in the reproduction of orchestral records.

The stylus lever or reed 25 made of mild steel or other suitable metal, is provided with a brass plate 26, secured to the lever in any convenient manner and carrying the usual socket 27 for the needle or stylus 28. The front 16 or open end of the sound-box has a flat facing 29 upon its rim, in which are inserted a pair of knife-edges or points 30 lying approximately in the plane of the diaphragm 18, to which the extremity of the lever is secured by a screw 31. The base plate 26 rests upon the points 30 so as to rock thereon during the vibration of the diaphragm and lever, seatings 32 of conical form or V-section (see Figure 3) being formed in the plate 26 to receive the points 30.

Between the seatings 32 of the points 30 and on opposite sides of the needle socket 27, the plate 26 is formed with apertures 33, 34 of approximately rectangular shape, in which are bedded the springs 35, serving to hold the plate against the points 30 and control its vibratory movement. These springs are preferably made of whalebone, in accordance with my prior United States patent specification No. 1,409,047, and composed of a plurality of laminations or leaves; the centres of the springs are secured against the facing 29 by screws 36 and their extremities bear upon the sides of the plate 26 at the ends of the apertures 33, 34, the bowed portions near the centres of the springs bedding down into the apertures of the base plate, as shown in Figure 2.

Having thus described my invention, what I claim is:—

1. A sound-box, comprising a body, a diaphragm mounted therein, a stylus lever rockably mounted upon said body and connected to said diaphragm, a base plate connected to said stylus lever, said base plate formed with apertures, and control springs secured to said body, said springs fitting in said apertures and pressing upon said base plate at opposite sides of the axis of its rocking movement. 30
2. A sound-box comprising a body, a diaphragm mounted therein, a stylus lever connected to said diaphragm, pivots mounted upon said body, a base plate connected to said stylus lever, said plate resting upon said pivots, and springs holding said plate in contact with said pivots, said springs fitting in apertures in said plate and pressing upon said base plate at opposite sides of the axis of said pivots. 35
3. A sound-box comprising a body, a diaphragm mounted therein, a stylus lever connected to said diaphragm, pivots mounted upon said body, a base plate connected to said stylus lever, said plate resting upon said pivots, springs holding said plate in contact with said pivots, said springs fitting in apertures in said base plate, and means for securing the centres of said springs to said body, the extremities of said springs engaging the sides of said base plate at opposite ends of said apertures and adapted to control the rocking motion of said lever. 40
4. In a gramophone sound-box, a stylus lever comprising an arm, means for connecting said arm to the diaphragm, a base plate connected to said lever pivots for rocking movement of said plate, said pivots being aligned approximately in the plane of the diaphragm, means for securing a needle to the base plate, said base plate being formed with apertures of approximately rectangular shape located symmetrically on either side of said needle securing means and extending across the axis on which said plate is adapted to rock, laminated springs spanning said apertures, and means for securing the centres of said springs to said body, said springs controlling the rocking motion of said lever. 45

ARTHUR FREDERICK RICHMOND COTTON.
